(57) **CLAIM**

The ornamental design for a wheel chair cushion, as shown and described.

DESCRIPTION

FIG. 1 is a front perspective view of a wheel chair cushion showing the new design;

FIG. 2 is a top plan view thereof;

FIG. 3 is a bottom plan view thereof;

FIG. 4 is a right elevation view thereof;

FIG. 5 is a left elevation view thereof;

FIG. 6 is a front elevation view thereof; and,

FIG. 7 is a back elevation view thereof.

The broken lines in the drawings are for the purpose of illustrating portions of the article that form no part of the claimed design.
